UNITED STATES PATENT OFFICE.

CHARLES B. MITCHELL, OF FRANKLIN, TEXAS.

SAFETY DEVICE FOR RAILWAYS.

1,004,806.

Specification of Letters Patent.

Patented Oct. 3, 1911.

Application filed May 9, 1910. Serial No. 560,138.

To all whom it may concern:

Be it known that I, CHARLES B. MITCHELL, a citizen of the United States, residing at Franklin, in the county of Robertson and 5 State of Texas, have invented a new and useful Safety Device for Railways, of which the following is a specification.

This invention has reference to improvements in safety devices for railways and is 10 designed to provide a device which will positively operate the controlling devices of a railway locomotive whether of steam or electric type, if danger conditions within a predetermined zone exist, each train or car establishing a danger zone within prescribed 15 limits which will operate to arrest the progress of another car or train approaching such zone, the invention being capable of operating to any desired distance from the 20 train being protected.

The invention will be best understood from a consideration of the following description taken in connection with the accompanying drawings forming a part of 25 this specification, in which drawings:

Figure 1 is a diagrammatic representation of the invention as applied to a railway system, the controlling devices of an ordinary locomotive as arranged for coaction with 30 the devices of the present invention being also diagrammatically represented. Fig. 2 is a sectional view of the train engaged devices at the side of the roadbed. Fig. 3 is a plan view of the structure of Fig. 2. Fig. 4 is a detail view of an engine carried element. Fig. 5 is an elevation partly in section and viewed from the side of the structure of 35 Fig. 2 remote from the track, of the train engaging devices.

Referring to the drawings there is shown in Fig. 1 an indication of a locomotive 1 with a throttle lever 2 and an engineer's air brake valve 3.

The throttle lever 2 is under the control 45 of a pneumatic operating member 4 and the valve 3 is under the control of a pneumatic operating member 5, the arrangement being such that the member 4 will operate to move the throttle lever 2 to the shut off position 50 and then the member 5 will operate the valve 3 to apply the brakes in the usual manner. The pneumatically operated members 4 and 5 are assumed to receive air under pressure through a pipe or conduit 6 coming 55 from a source of air supply such as the main

reservoir of the air brake system and in this pipe there is a valve 7 under the direct control of a rod 8 which may extend above the cab of the engine and be there provided with an angle or crank extension 9 for a 60 purpose which will presently appear. When the valve 7 is opened, air passing through the pipe 6 will actuate the pneumatic member 4 to cut off steam from the engine and as soon as this is done the 65 member 5 receives the air and the valve 3 is actuated in a manner to apply the brakes so that steam is cut off from the engine and the brakes applied in succession and the engine or train is brought to a stand- 70 still.

At predetermined points along the line of way are stop members 14 constrained by gravity or otherwise to assume a position in the path of the crank extension 9 of the 75 valve rod 8 on the engine. In operative relation to each stop member 14 is a lock bar 15 so arranged as to engage the stop member 14 and hold it rigidly in position to be engaged by the crank extension 9 80 on the engine so that on such engagement the valve rod 8 will be caused to make about a quarter turn thus opening the valve 7 and causing the actuation of the train controlling devices in the manner described. 85 Normally, however, the lock member or bar 15 is under the control of an electro-magnet 16 the armature 17 of which is made fast to the bar 15 so that when the magnet 16 is energized the bar 15 is withdrawn from 90 engaging relation with the stop member 14 which latter may be provided with a notch 18 into which the bar 15 will drop, if it be considered that the parts respond to the action of gravity, when the magnet 16 is 95 not energized, thus under these circumstances locking the stop member 14 against movement and thereby causing the opening of the valve 7 to thereby shut off power and apply the brakes.

At suitable points along the line of way are parallel guide members 19 and 20 shown as in the form of curved channel strips in Figs. 2, 3 and 5. It is not absolutely essential that these channel strips be used, but as 105 will hereinafter appear they serve to guide and protect certain parts entering into the invention. It will be understood that these strips may be replaced by plane strips so far as the operation of the invention is con- 110

cerned. In the axis of curvature of the strips there is provided a pivot support 21 carrying an arm or lever 22 traversing a guide strip 23 which serves to relieve the 5 pivot support 21 of undue strain. The arm 22 may be hollow and be traversed by a rod 24 extending entirely through the arm 22 and carrying at the end adjacent to the strips 19, 20 a cross arm 25 of such length 10 and so located as to engage with one end the strip 19 and the other end the strip 20 when at an angle to the length of both of these strips. One end of the cross arm 25 is provided with a terminal insulating block 26 15 while the other end is adapted to make electrical contact with the strip 19 or 20 as the case may be.

At the end of the arm 22 remote from the cross arm 25 the pivot rod 24 projects and is 20 there provided with a crank extension 27 to which is attached one end of a spring 28, the other end of which is attached to a fixed point, the relation of the spring 28 and the crank arm 27 to the rod 24 being such as to 25 maintain the conducting end of the cross arm 25 in engagement with the strip 19 or the strip 20 in accordance with the position of the arm 25, which is also held by the spring 28 in the position to which it was moved by the 30 last passing train.

The arm 25 is provided with a cross pin 29 and is in the path of a finger 30 on an arm 31 carried by the engine 1, this engine being represented in Fig. 2 by a wheel and 35 a portion of the truck. The finger 30 may be mounted on a pivot 32 carried by the arm 31 and be centralized by a spring 33 which permits the finger 30 to yield upwardly or downwardly about the pivot 32. The 40 arm 22 is centralized with reference to the strips 19 and 20 by the guide strip 23 which is provided with a longitudinal slot through which the arm 22 passes and the said arm is held by two springs 34, each fast at one end 45 to the arm 22 and at the other ends to the strips 23 on opposite sides of the arm 22. The springs 34 will yield to any force tending to turn the arm 25 on the pivot support 21 and thus when the arm 25 is engaged by 50 the finger 30 of a rapidly moving train the springs 34 act as elastic buffers permitting a horizontal yielding of the arm 22 to the impact of the finger 30. The purpose of the finger 30 is to cause the turning of the arm 25 on the axis of the pivot rod 24 when the 55 arm 25 is engaged by the finger 30 on the moving train so that if the conducting end of the arm 25 be at the time in engagement with the strip 19 it will be moved into engagement with the strip 20 and the insulating end 26 will be moved from the strip 20 to the strip 19, the spring 28 permitting the 60 movement and holding the arm 25 in its new position. Since the arm 25 is always 65 inclined away from an oncoming finger 30,

the latter because of its yielding mounting will ride along the arm 25 until it strikes the cross pin 29 and will then turn the arm to its new position thus reversing its electrical connections. The finger 30 usually 70 travels in a line about on a level with the pivots of the arms 25 although some variation from this level is not material. The arm 25 may be insulated in any suitable manner and is coupled by a conductor 35 to one side of the adjacent magnet 16 while the other side of this magnet is connected either to a battery 36 or other suitable source of electric current which in turn is connected to ground by a conductor 37 or this magnet 80 is connected directly to ground by a conductor 38, these two arrangements being provided at the opposite ends of a block section. The strips 19, at the two ends of a block section are connected together by a 85 conductor 39 while the strips 20 are likewise connected by a conductor 40.

Under normal working conditions the arms 25 at the two ends of a block section have their conducting ends in engagement 90 with the like strips 19 or 20 at the two ends of the block. Under these conditions there is established a circuit from the battery 36 to the adjacent magnet 16 thence to the adjacent arm 25 and by the latter to say, 95 the strip 19 there located, thence by the conductor 39 to the other strip 19 thence by the arm 25 there located to the respective conductor 35 thence to the magnet 16 at the last named end of the block section, thence by 100 the conductor 38 to ground and back by the conductor 37 to the battery 36. Under these circumstances the two magnets 16 at the ends of the block section are energized and their armatures 17 are attracted so that 105 the bars 15 are out of engagement with the stop members 14 and the latter are then free to move under the action of a small force so that if under these circumstances a stop member 14 is engaged by the end 9 of the 110 rod 8 the member 14 will yield. If however either arm 25 be moved from its normal position to the reverse position then the circuit through the magnets is broken and both 115 magnets become deenergized and both stop members at the opposite ends of the block section become locked rigidly so that the valve 7 of a passing train is actuated and the controlling means of the train are operated in a manner to bring the train to a 120 standstill.

If it be assumed that a train enters a block equipped with the present invention then the entering train will first engage the stop member 14 at the entrance of the block 125 and, the block being clear, this member 14 is in the unlocked position and the valve 7 will not be actuated so that the train will enter the block without trouble. This will, of course, indicate to the engineman that the 130

block is clear. As soon, however, as the train has entered the block the finger 30 carried by the train engages the adjacent arm 25 and the latter is moved on its pivot support in a direction to break the circuit to both magnets 16 so that both become de-energized and the train is protected at both ends from oncoming trains, either approaching the train within the block from the front or from the rear.

10 Ultimately the train reaches the other end of the block but before it can come into engagement with the stop member 14 there located the finger 30 on the train first engages the arm 25 located at the outgoing end of the block and this arm is swung on its pivot so that its conducting end is brought into engagement with the strip 19 or 20 electrically connected with the strip 19 or 20 into engagement with which the arm 25 at the entering end of the block was moved by the passing train. This results in causing the energization of both magnets 16 and the release of both stop members 14 so that the train in the block is free to pass out therefrom and any train following is free to pass into the block lately occupied by the train under consideration. By having the stop members 14 of adjacent blocks in overlapping relation and properly spaced apart no train can approach into dangerous proximity to another since both trains will be stopped before the danger zone is entered.

15 The train controlling mechanism shown in the drawings forms in itself no part of the present invention and any type of train controlling device may be used, it only being necessary to respond to the stop members 14 along the line of way either above the trains 20 or to one side thereof or even below the trains, the situation of these stop devices not being material to the operation of the invention.

What is claimed is:—

1. In a safety device for railways, mechanical stop members at the ends of block sections electro-magnetic means for rendering the stop members inactive, switches responsive to passing trains, and located closer together than are the stop members, and a single charged electric circuit including the switches and said electro-magnetic means controlling the stop members.

2. In a safety device for railways, mechanical stop members at the ends of block sections, locks for said stop members, electro-magnets normally holding the locks in the inactive position, electric switches responsive to passing trains and located closer together than are the stop members, and a single charged electric circuit including the switches and electro-magnets controlling the locks for the stop members.

3. In a safety device for railways, mechanical stop members at the ends of block stations, locks for said stop members, electro-magnets controlling the locks for the stop members and holding them normally in the inactive position, a normally closed charged circuit including the magnets, pairs of circuit terminals in said circuit at the ends of the block stations but nearer together than the stop members, switches in said circuit, each movable into engagement with either of the terminals of a respective pair, and train carried means for moving said switches from one terminal of a pair to the other.

In testimony that I claim the foregoing as my own, I have hereto affixed my signature 80 in the presence of two witnesses.
